ADJUSTABLE STEEL VAULT

Filed June 21, 1928

UNITED STATES PATENT OFFICE

ROLF S. GARVER, OF PORTIS, KANSAS

ADJUSTABLE STEEL VAULT

Application filed June 21, 1928. Serial No. 287,216.

This invention relates to a steel vault designed to be used in banks and other business houses for the protection of employees against robbers or bandits, and the general object of the invention being to provide a vault structure mounted upon wheels whereby it may be readily shifted from one portion of a bank or business house to another and into which an employee can step in case of robbery, the vault being equipped with firearms and being formed with loop-holes for the discharge thereof.

A further object is to provide a vault of this character formed in two sections, one of which is telescopic within the other and providing means whereby the two sections may be shifted relative to each other to thus increase or decrease the size of the vault in accordance with the requirement for space or convenience.

Other objects will appear during the course of the following description.

The invention is illustrated in the following drawings in which—

Fig. 1 is a vertical sectional view of a safety vault constructed in accordance with my invention;

Fig. 2 is an end elevation of the vault;

Fig. 3 is an elevation of the opposite end of the vault;

Fig. 4 is a fragmentary section on the line 4—4 of Fig. 1.

Referring to these drawings it will be seen that the vault consists of two sections A and B, the section B being telescopic within section A. Each of these sections is formed of sheet steel of any desired or required thickness and each section may be constructed in any approved manner as regards the fitting together of the sheet steel and the structural features thereof. The vault is provided in either one of its walls 10 with a doorway 11 having a door 12 which will preferably be fastened or latched from the interior of the section. This door may be hinged in any suitable manner. The two sections are each provided with floor engaging rollers 13 whereby the sections may be supported and the smaller section B may be provided with rollers 14 engaging with tracks 15 formed in

the other section, so that the two sections may have easy sliding engagement one with the other to permit one to be adjusted within the other. The top walls of both sections are provided with ventilating openings 16 which may be in the form of louvres or any suitable ventilating openings may be used, it being preferable that these ventilating openings may be so constructed as to prevent robbers or bandits from shooting into the interior of the vault through these openings. The front wall of the section B may be provided with a longitudinally extending window 17, while the section A or outer section is formed with a longitudinally extending opening 18 adapted to align with the opening of the window 17, this opening 18 preferably extending to the open end of the section A, thus the window 17 will be disclosed through the opening 18 in any position of the section B relative to section A.

A counter or shelf 19 is mounted upon section B beneath the opening 17 and sliding metallic shutters or shields 20 which are mounted upon the section A so that they may be slid across all that portion of the opening 18 which is inward of the window 17, suitable locking devices as for instance a latch or hook 20^a being, of course applied for the purpose of locking the shutters in their adjusted positions. The window 17 is designed to be used by the bank officer in conducting business.

For the purpose of adjusting the two sections with relation to each other, I have illustrated a cable 21 which is attached at one end to the closed end of section A and extends longitudinally along the section A beneath the roof thereof or in any convenient position, and extends into section B and is engaged with a winding roller or winch 22 mounted upon the wall 23, which closes the end of this section. Suitable means, as for instance a pawl engaging the winch, will hold the winch in its set position and the cable wound upon the winch and thus will hold the sections in their adjusted positions.

The vault may be made of a standard size, as for instance, seven feet long by six and one-half feet in height when elongated to

its full size, but can be reduced in length to three and one-half feet by winding up on a small chain or cable 21, previously referred to. Two rods 24 extend from the outer walls 5 of the opposite sections A and B, these rods passing through a clamp 25 having set screws 26 whereby the rods may be held in adjusted positions to hold the sections firmly in place against telescopic movement in either direction.

10 These rods extend along the sides of the sections two feet from the floor. The walls of the vault may be formed at intervals with port holes or loop holes 27 and the window 15 17 may be equipped with a steel shutter or shield 28 adapted to be dropped or lowered behind the window for the protection of the occupant in time of danger. The port holes will, however, permit the occupant to use his 20 firearms in attacking the robbers.

What I claim is—

1. A vault for business houses and banks formed of two telescopic metallic sections having means for entrance and exit, and 25 means whereby said sections may be adjusted into each other and held in their adjusted positions, the inner section being formed with a window and the outer section having a longitudinally extending opening alining 30 with the window whereby the window will be exposed in any adjusted positions of the two sections.

2. A vault for business houses and banks formed of two telescopic metallic sections 35 having means for entrance and exit, and means whereby said sections may be adjusted into each other and held in their adjusted positions, the inner section being formed with a window and the outer section having a longitudinally extending opening alining 40 with the window whereby the window will be exposed in any adjusted positions of the two sections, the end of said opening remote from the inner section being provided with 45 shields adapted to be adjusted to close the space between the window opening of the first named section and the adjacent edge of the wall of the second named section.

3. A vault of the character described 50 formed of two telescopic sections and being formed to provide means for entrance and exit, and means for shifting the sections with relation to each other comprising a flexible member attached to one of said sections, and 55 a winch on the other section with which the flexible member is engaged, and releasable means for holding the two sections against outward movement.

In testimony whereof I hereunto affix my 60 signature.

ROLF S. GARVER.
